UNITED STATES PATENT OFFICE.

CHARLES S. MILLS, OF NORWOOD, MASSACHUSETTS.

EXHAUST-NOZZLE.

No. 822,216.

Specification of Letters Patent.

Patented May 29, 1906.

Application filed August 12, 1905. Serial No. 273,858.

To all whom it may concern:

Be it known that I, CHARLES S. MILLS, a citizen of the United States, residing at Norwood, in the county of Norfolk and State of Massachusetts, have invented new and useful Improvements in Exhaust-Nozzles, of which the following is a specification.

This invention relates to exhaust-nozzles for steam-engines, and is particularly adapted for use in locomotives.

The object of the invention is to increase the draft in the exhaust-passages leading from the cylinders of the engine and to thus reduce the back pressure in the said cylinders.

The invention consists in the combination and arrangement of parts set forth in the following specification and particularly pointed out in the claims thereof.

Referring to the drawings, Figure 1 is a vertical transverse section, partly in elevation, taken across the cylinders, smoke-box, and smoke-stack of a locomotive with my improved exhaust-nozzle attached thereto. Fig. 2 is a side elevation of my improved exhaust-nozzle. Fig. 3 is a section, partly in elevation, taken on line 3 3, Fig. 1, looking downwardly in said figure. Fig. 4 is a side elevation, partly in section, of a modified form of my invention. Fig. 5 is a section, partly in elevation, taken on either line 5 5, Fig. 4, viewed from the front of the locomotive. Fig. 6 is a section, partly in elevation, taken on line 6 6, Fig. 5, looking downwardly in said figure. Fig. 7 is a section, partly in elevation, taken on line 7 7, Fig. 5, looking downwardly in said figure. Fig. 8 is a plan view of another modified form of my invention. Fig. 9 is a section, partly in elevation, taken on line 9 9, Fig. 8. Fig. 10 is a section, partly in elevation, taken on line 10 10, Fig. 8. Fig. 11 is a section, partly in elevation, taken on line 11 11, Fig. 9.

Like numerals refer to like parts throughout the several views of the drawings.

In the drawings, Figs. 1 to 3, inclusive, 15 is the smoke-box of a locomotive of any suitable construction, 16 the smoke-stack, and 17 and 18 the right and left hand cylinders, respectively, of a locomotive.

19 is the passage for exhaust-steam leading from the opposite ends of the cylinder 17 upwardly to the bottom of my improved exhaust-nozzle 20 at the right side thereof.

21 is a passage for exhaust-steam leading 55 from opposite ends of the cylinder 18 to the

bottom of the nozzle 20 at the left-hand side thereof.

The exhaust-nozzle 20 consists of three parts—viz., an intermediate conical pipe 22, an outlet-tip 23, and a base 24. The outlet-tip 23 is fastened to the top of the intermediate pipe 22 by bolts 25 25. The intermediate chamber 22 is fastened to the top of the base 24 by bolts 26 26. The passage 19 opens into passage 27, provided in the base 24, 65 and the passage 21 opens into passage 28, provided in said base. These passages 27 and 28 extend upwardly and terminate adjacent to the lower end of said intermediate pipe. The outlet 29 of the passage 28 surrounds the 70 outlet 30 of the passage 27, and the area of the annular space of the outlet 29 is equal to the area of the outlet 30. The area of the passage through the outlet-tip 23 is also preferably equal to the area of the outlet of the 75 passage 27. The periphery of the outlet end of the passage 27 is conical in form and parallel to the interior conical wall of the intermediate pipe 22, and this conical end projects upwardly into the interior of the said intermediate pipe. 80

The operation of my improved exhaust-nozzle is as follows: Exhaust-steam passing through the passages 19 and 21 and out of the outlet 30 causes a suction in the passages 27 and 28, thus assisting the live steam in 85 the cylinder 18 by decreasing the back pressure in said cylinder and in like manner steam passing upwardly through the passages 21 and 19, thus reducing the back pressure in the cylinder 17. The intermediate chamber 90 or pipe 22 forms a combining-chamber in which the steam from the passages 27 and 28 becomes thoroughly mixed before passing out through the outlet-tip 23 into the smoke-box 15, and thence upwardly and outwardly 95 through the smoke-stack 16.

The construction of the nozzle in three parts, as hereinbefore described, is very advantageous not only in the working or practical operation of the device in its connection 100 with the exhaust-passages leading from the cylinders, but is also of great advantage and economy of construction, for the reason that the outer periphery of the outlet end 30 of the passage-pipe 27 is readily accessible for 105 the purpose of machining the outer periphery and obtaining the correct diameter and angle with relation to the conical interior wall of the intermediate pipe 22. It is also evident that the intermediate pipe 22 may be 110

conveniently finished and machined as well as the interior of the outlet-tip 23, and again if it is desired to change the outlet-tip to obtain an outlet area of different extent it may 5 be readily done by removing one outlet-tip and substituting another having the required outlet area.

In the form of my invention hereinbefore described two passages 27 and 28 are provided in the interior of the base 24. In Figs. 4 to 7, inclusive, I have illustrated a modified form of my invention in which more than two passages are provided in the base for the exhaust-steam, and in this form of my invention 15 20' is the nozzle formed in three parts—viz., the intermediate conical pipe 22', the outlet-tip 23', and the base 24'. The outlet-tip 23' is fastened to the intermediate pipe 22' by bolts 25', and the intermediate pipe 22' is fastened to the base 24' by bolts 26'. In this form of my invention the base 24' is provided with two passages for exhaust-steam 27' 27' at the right-hand side thereof, these 25 passages being connected by a passage for exhaust-steam similar to the passage 19, Fig. 1, to the right-hand cylinder of the locomotive. Said base is also provided with an exhaust-passage 28' at the left-hand side thereof, which passage is connected by a suitable 30' passage for exhaust-steam similar to the passage 21, Fig. 1, to the left-hand cylinder of the locomotive. The passages 27' 27' terminate at their upper ends in two conical outlets 30' 30', and the passage 28' is bifurcated 35 at its upper end, as seen in Fig. 4, to form two outlets 29' 29', each of which surrounds one of the outlets 30' 30'. The intermediate chamber 22' is also provided with two conical interior passages 31 31, which connect 40 with two passages 32 32, extending through the outlet-tip 23'.

In Figs. 8 to 11 I have illustrated another modified form of my invention, in which 20' is the nozzle, which is made in three parts—45 viz., the intermediate conical pipe 22', the outlet-tip 23', and the base 24'. The outlet-tip is fastened to the intermediate pipe by bolts 25', and the base is fastened to the intermediate pipe by bolts 26'. In this form 50 of my invention the lower portion of the base 24' is provided with four passages, two of said passages 27' 27' being connected by suitable passages to the right-hand cylinder of the locomotive and the other two passages 55 28' 28' being connected by suitable passages to the left-hand cylinder of the locomotive. One of the passages 27' extends upwardly and terminates in a conical end 30', surrounded by the outlet 29' of the passage 28'. 60 (See Fig. 9,) while the other passage 27' extends upwardly, and its outlet 30' surrounds the conical outlet end 29' of the passage 28'. (See Fig. 10.)

In all of the various forms of my invention 65 hereinbefore described, however, the nozzles

are made in three parts, and the outlet end of the exhaust-passage from one of the cylinders surrounds the outlet end of a passage leading from the other cylinder.

What I claim, and desire by Letters Patent 70 to secure, is—

1. An exhaust-nozzle for steam-engines, comprising in its construction three parts fastened together, viz, an intermediate pipe having a conical interior chamber, a base fast to the lower end thereof, and an outlet-tip fast to the upper end thereof, said base provided with two steam-passages therein, the outlets of said passages terminating adjacent to the lower end of said intermediate pipe and one 80 of said outlets surrounding the other outlet, the areas of said outlets equal one to the other, the upper end of the inner outlet projecting upwardly into the interior of said intermediate pipe and having a conical periphery, said periphery parallel to the interior wall of said conical interior chamber. 85

2. An exhaust-nozzle for steam-engines, comprising in its construction three parts fastened together, viz, an intermediate pipe, a 90 base fast to the lower end thereof, an outlet-tip fast to the upper end thereof, said base provided with two steam-passages therein, the outlets of said passages terminating adjacent to the lower end of said intermediate 95 pipe one of said outlets surrounding the other outlet and means for detachably fastening said parts together.

3. An exhaust-nozzle for steam-engines, comprising in its construction three parts fastened together, viz, an intermediate pipe provided with a plurality of passages therein, a base fast to the lower end of said intermediate pipe and an outlet-tip fast to the upper end thereof and provided with a plurality of 100 outlet-passages therein, said base provided with a plurality of steam-passages therein, the outlets of said steam-passages terminating adjacent to the lower end of said intermediate pipe, said outlets arranged in pairs, one 105 member of each of said pairs surrounding the other member of its respective pair. 110

4. An exhaust-nozzle for steam-engines, comprising in its construction three parts fastened together, viz, an intermediate pipe provided with a plurality of passages therein, a base fast to the lower end of said intermediate pipe and an outlet-tip fast to the upper end thereof and provided with a plurality of 115 outlet-passages therein, said base provided with a plurality of steam-passages therein, the outlets of said steam-passages terminating adjacent to the lower end of said intermediate pipe, said outlets arranged in pairs one 120 member of each of said pairs surrounding the other member of its respective pair, and the area of one outlet of each pair being equal to the area of the other outlet of the same pair. 125

5. An exhaust-nozzle for steam-engines comprising in its construction three parts fas- 130

tened together, viz, an intermediate pipe provided with a plurality of conical inner chambers, a base fast to the lower end thereof, an outlet-tip fast to the upper end thereof and provided with a plurality of outlet-passages therein, said base provided with a plurality of steam-passages therein the outlets of said steam-passages terminating adjacent to the lower end of said intermediate pipe, said outlets arranged in pairs, one member of each of said pairs surrounding the other member of its respective pair, the areas of the outlets of each of said pairs being equal one to the

other, the upper end of the inner outlet of each pair projecting upwardly into one of 15 said conical interior chambers respectively and having a conical periphery, said periphery parallel to the interior wall of its respective conical interior chamber.

In testimony whereof I have hereunto set 20 my hand in presence of two subscribing witnesses.
